UNITED STATES PATENT OFFICE.

LEO J. GRUBMAN, OF NEW YORK, N. Y., ASSIGNOR TO VOICES INCORPORATED, OF NEWARK, NEW JERSEY, A CORPORATION OF DELAWARE.

SOUND DEVICE.

Application filed December 17, 1925. Serial No. 75,980.

My invention relates to improvements in sound devices and more particularly to sound devices to be used in toys such as dolls for the purpose of causing them to emit sound like "ma-ma," "pa-pa," etc. The main object of the invention is to provide a device of the class described, which is not only simple, easy and cheap to manufacture but which is also efficient in operation and not likely to get out of order. Further and more specific objects, features and advantages will more clearly appear from the detailed description given below taken in connection with the accompanying sheet of drawings which illustrate one embodiment of my improvements.

In the drawings, Fig. 1 is a vertical section and Fig. 2 is a plan of the cap member forming the sound chamber of the device.

Referring to the drawings, 3 represents a cylindrical casing of cardboard or other suitable material closed at one end by a sheet metal circular cover 4 and at the other end by sheet metal circular cover 5 perforated as at 6. 7 represents a tubular bellows of rubberized cloth or other suitable material, one end of the bellows being clamped and secured to one end of the casing by the cover 4 as at 8 whereby the cover 4 forms a head closing one end of the bellows. The other end of the bellows is clamped to a circular weighty disc or head 9 as at 10 by a sheet metal cap member 11, the cap 11 forming a sound chamber 12 in connection with and on top of the weighty head member 9. The weighty head 9 is adapted to slide back and forth in the casing by gravity to compress and distend the bellows whereby a compressible air chamber is formed. 13 represents a reed pipe inserted in an opening extending through the head 9, the reed pipe having a sound reed which is operated when the bellows is compressed in a manner well understood by those skilled in the art, the sound from the reed issuing into the sound chamber 12. 14 represents a flat guide post, the ends of which are held in position by engagement with recesses in the covers 4 and 5 respectively as at 15 and 16. The head 9 is provided with a slot 17 extending therethrough shaped like the cross section of the post 14, and through which slot the post 14 passes. The cap 11 is provided with a similar slot 18 through which the post 14 passes. Thus the weighty head and sound

chamber are guided by the post 14 in their movements back and forth to compress and distend the bellows.

The cap 11 is also provided with an opening 19 through which the sound issuing from the reed into the sound chamber may issue. As will be seen from Fig. 2 the slot 18 is in communication with and opens into the opening 19. The opening 19 is normally closed by a hemi-spherical valve 20. Extending within the sound chamber is a resilient coil spring 21 one end of which is connected to the valve 20 and the other end of which is anchored to the head 9 in the sound chamber at 22. It will be noted that the cap 11 is pressed inwardly about the opening 19 to form a concave seat for the valve and the lower face or surface of the valve which normally closes the opening 19 is convex. By this arrangement the valve 20 is supported solely by the resilient member or spring 21 and has a universal movement over the opening 19 on the outside of the sound chamber and with respect thereto, but in whatever direction the valve is moved away from its seat, the spring will always cause it to be properly reseated at the proper time. The post 14 is cut away at 23 and 24 to form a plurality of projections 25 and 26, and as the weighty head and sound chamber descend by gravity to compress the bellows the projection 25 will first engage the valve 20 causing it to be unseated whereby the sound from the reed will issue from the opening 19 and through the perforations 6 to the outside, producing, for example, a sound like "ma." When the weighty head descends so that the valve 20 comes opposite the part 24, the spring will return the valve to its normal or closed position thus terminating the sound issuing from the device. As the weighty head further descends by gravity the valve 20 will be engaged and rocked away from the opening 19 by the projection 26 and the valve will be maintained opened during the further compression of the bellows thus producing a longer sound, for example, like "ma" thus simulating the word, "ma-ma." The parts may be restored to their original position as shown in Fig. 1 by inverting the device whereby the weighty head will distend the bellows by gravity.

While I have described my invention in great detail and with respect to a preferred

form thereof, I do not desire to be limited to such details or form since many changes and modifications may be made and the improvements embodied in widely different forms without departing from the spirit and scope thereof in their broader aspects. Hence I desire to cover all modifications and forms coming within the language or scope of any one or more of the appended claims.

What I claim as new and desire to secure by Letters Patent, is:

1. A sound device having in combination a casing, a tubular bellows in the casing, one head of the bellows being secured with respect to the casing and the other head of the bellows being movable by gravity back and forth in the casing to compress and distend the bellows, a sound chamber carried with the movable head of the bellows, a sound reed, the sound from which is adapted to issue into the sound chamber upon operation of the bellows, said sound chamber having an opening for the issuance of sound therefrom, a valve having a convex face for closing said opening, a coiled spring extending in said sound chamber, one end of said spring being attached to said valve and the other end of the spring being anchored in said sound chamber to normally tend to close said valve, and a guide post fixed with respect to the casing and along which movable head slides, said guide post having projections for engaging and operating said valve.

2. A sound device having in combination a casing, a tubular bellows in the casing, one head of the bellows being secured with respect to the casing and the other head of the bellows being slidable by gravity back and forth in the casing to compress and distend the bellows, a sound chamber carried with the movable head of the bellows, a sound reed the sound from which is adapted to issue into the sound chamber upon operation of the bellows, said sound chamber having an opening for the issuance of sound therefrom, a valve having a semi-spherical surface for closing said opening, a resilient member extending within the sound chamber and anchored therein, one end of said re-

silient member being connected to the valve to normally close the same, and a member fixed with respect to the casing and having projections for engaging and operating said valve.

3. A sound device having in combination a casing, a tubular bellows in the casing, one head of the bellows being secured with respect to the casing and the other head of the bellows being slidable by gravity back and forth in the casing to compress and distend the bellows, a sound chamber carried with the movable head of the bellows, a sound reed the sound from which is adapted to issue into the sound chamber upon operation of the bellows, said sound chamber having an opening for the issuance of sound therefrom, a valve having a convex surface for closing said opening on the outside of said sound chamber, a spring in said sound chamber, one end of the spring being connected with said valve to normally close said valve, and means for operating said valve responsive to the operation of the bellows to actuate the sound reed.

4. A sound device having in combination a casing, a tubular bellows in the casing, one head of the bellows being secured with respect to the casing and the other head of the bellows being slidable by gravity back and forth in the casing to compress and distend the bellows, a sound chamber carried with the movable head of the bellows, a sound reed the sound from which is adapted to issue into the sound chamber upon operation of the bellows, said sound chamber having an opening for the issuance of sound therefrom, a valve having a convex surface for closing said opening on the outside of said sound chamber, a spring in said sound chamber, one end of the spring being connected with said valve to normally close said valve, and means for operating said valve responsive to the operation of the bellows to actuate the sound reed, said valve having a universal movement over said opening.

In testimony whereof I have signed my name to this specification.

LEO J. GRUBMAN.
